UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 14,577, dated January 29, 1884.

Application filed November 24, 1883. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an open-face letter, the cross-lines of which, as in the A, B, E, F, H, and P, are inclined, supported upon a tile-like groundwork.

The character of the design is preserved in the numerals.

In connection with the font are shown a series of ornamented adjuncts, numbered from 1 to 14, inclusive, and reference is made to the typographic impression, which shows fac-similes of the faces of these ornamented adjuncts. 20

Having now described my invention, I claim as new—

The design for a font of printing-type, substantially as shown and described.

HERMAN IHLENBURG.

In presence of—

C. F. HUCH,
W.M. B. MACKELLAR.
